W. E. FARLEY

MEANS FOR LUBRICATING AIR COMPRESSING ENGINES

Filed Feb. 10, 1923

William E. Farley

By Watson E. Coleman
Attorney

UNITED STATES PATENT OFFICE.

WILLIAM E. FARLEY, OF EL RENO, OKLAHOMA.

MEANS FOR LUBRICATING AIR-COMPRESSING ENGINES.

Application filed February 10, 1923. Serial No. 618,281.

To all whom it may concern:

Be it known that I, WILLIAM E. FARLEY, a citizen of the United States, residing at El Reno, in the county of Canadian and 5 State of Oklahoma, have invented certain new and useful Improvements in Means for Lubricating Air-Compressing Engines, of which the following is a specification, reference being had to the accompanying 10 drawings.

This invention relates to lubrication, and particularly to means for lubricating the air ends of air compressing engines, and the object of the invention is to provide means whereby the oil cups and oil 15 swabs ordinarily used in oiling the air end of air compressors are dispensed with and lubrication is secured by conducting the exhaust steam as it comes from the steam 20 end of the compressing engines through a condenser pipe into the air end of the compressor, thus carrying lubricant which is contained in the steam into the compressing cylinders or cylinder.

25 A further object is to provide means whereby the condensed steam carrying the lubricant is retarded just prior to its entrance into the air end of the compressor engine so as to reduce the extreme heat of 30 the exhaust steam which would otherwise cause the lubricant to be destroyed.

Other objects will appear in the course of the following description.

My invention is illustrated in the accompanying drawings, wherein:—

Figure 1 is a diagrammatic elevation of a double acting steam engine with double acting air compressors connected thereto and showing my lubricating device applied 40 thereto;

Figure 2 is a fragmentary top plan view of the cylinders 11 and 12 with my lubricating device attached thereto;

Figure 3 is a fragmentary enlarged section on the line 3—3 of Figure 2;

Figure 4 is a fragmentary enlarged section on the line 4—4 of Figure 2.

Referring to these drawings, it will be seen that I have illustrated my lubricating system in connection with an air pumping engine having a low pressure steam cylinder, a high pressure steam cylinder, a high pressure air cylinder, and a low pressure air cylinder, the piston of the low pressure cylinder being directly connected to the piston of the high pressure cylinder, and

the same being true of the low pressure steam and air cylinders.

10 designates the high pressure steam cylinder, 11 the low pressure steam cylinder, 12 the low pressure air cylinder, and 13 the high pressure air cylinder, 14 designating the piston rods connecting the pistons of the two cylinders. I have illustrated the steam cylinders and air cylinders diagrammatically, as it will be understood that this lubricating system might be applied to many different forms or types of air compressing cylinders.

From the low pressure steam cylinder extends the usual steam exhaust pipe 15, and to this steam exhaust pipe 15 is connected a condenser pipe 16. This is illustrated as connected to the exhaust pipe 15 by a nipple 17 and chamber 18, and within the 75 chamber is threaded an annulus 19 having a relatively small orifice discharging into the condenser pipe. The condenser pipe may be of any required length, diameter or form in order to suit different conditions 80

or locations of compressing engines and may be either a straight pipe or formed with coils. I have illustrated it, however, as a straight pipe and as extending diagonally downward from the exhaust pipe on one 85 side of the low pressure steam cylinder to the low pressure air cylinder 12 to which it is connected by an elbow 20 and a collar or coupling 21.

The lower end of the condenser pipe adjacent the low pressure air 90 cylinder, as illustrated in Figure 4, is both exteriorly and interiorly threaded, the exterior threads receiving the collar 21 and the interior threads receiving a nipple 22 having a longitudinally extending bore 95

which discharges by a very small orifice 23 toward the low pressure air cylinder. The bore 24 for a distance beyond this orifice 23 is relatively small and then is enlarged toward the extremity of the nipple away 100 from the orifice 23. The extremity of the nipple is beveled at 25. The purpose of this nipple is to retard and check the flow of condensed steam from the condenser pipe 16 to the low pressure air cylinder, 105 and to this extent the nipple 22 acts as a trap. The retardation of the condensed steam causes the retarded steam to cool before passing through the small orifice 23 and being admitted to the air end of the 110 compressing engine. It is necessary to do this because of the fact that the steam when

received from the exhaust pipe is at a relatively high degree of temperature and will cause the lubricant to be destroyed.

Preferably connected to the condenser 16 is a branch pipe 26 which is connected to the high pressure steam cylinder 13 by means of the collar 27 within which is disposed a feed control element consisting of the nipple 22 having the bore 23, the enlarged portion 24, and the beveled end 25, as previously described. In other words at the inlet of the pipe 16 into the low pressure air cylinder and at the inlet of the branch pipe 26 into the high pressure cylinder there is provided a feed control element of the character shown in Figure 4. Preferably there will be a fine mesh screen 28 disposed across the port admitting the steam from the exhaust pipe 15 into the condenser pipe 16. This will prevent any scale or any other foreign matter passing through the exhaust pipe into the condenser, which foreign matter might clog the small feed orifice in the feed control element. I have also illustrated a hard grease lubricator of conventional form, designated 29, as connected to the steam inlet pipe for the high pressure steam cylinder and have illustrated the ordinary air pump governor 30 connected to this steam inlet pipe.

This invention operates to catch any lubricant that may escape with the exhaust steam, retarding it with the condensed steam in the condenser and delivering it to the air cylinder of the air compressor. This lubricating mechanism may be used with any kind of lubricant whatsoever and may be used with a hard grease lubricator or with an oil lubricator, and it is to be particularly understood that it may be used with the present hydrostatic lubricator in universal use on all compressors at this time. Inasmuch as the particular form of lubricator forms no part of this invention, I have only illustrated the lubricator conventionally.

The object of the small port 19 at the inlet end of the condenser is to reduce the volume of exhaust steam entering the condensing pipe and to retard this steam. The feed control element illustrated in Figure 4 should be of such dimensions that it will cause the exhaust steam to be condensed into water before it passes into the low pressure air cylinder. The particular object in having the bore of the controlling element 22 of different diameters is that this also acts to retard the passage of steam from the condensing pipe into the air cylinder and this retardation causes the steam to condense. The object in having the extremity of the member 22 beveled is to prevent shoulders being formed at this place and do away with any abrupt obstruction which would allow water to pass by the feed element and stand between the feed element and the pipe.

The steam condenses into water up to a point where it will overflow and flow back into the feed element. The steam is completely condensed up to a point at least two inches above the feed element. This apparatus may be used on any steam or air pressure engine not only for locomotive purposes but for any compressor engine operated by steam, either single cylinder or compound.

With this system the same lubricant is used for lubricating the steam end of the compressor as for lubricating the air end of the compressor engine, thus securing a considerable economy and doing away absolutely with the necessity of using oil cups and oil swabs for oiling the air end of the compressor engine.

While I have illustrated a particular arrangement of condenser pipe, I do not wish to be limited thereto as it is obvious that modifications may be made within the scope of the appended claims and particularly that the condenser pipe may be of various forms without departing from the principle of the invention.

I claim:

1. The combination with a steam cylinder having an exhaust pipe and an air compressing cylinder operated thereby, of means for lubricating the latter comprising a tubular steam condensing member operatively connected at one end with the exhaust pipe and at its other end to the air cylinder.

2. The combination with a steam cylinder having an exhaust pipe and an air compressing cylinder operated thereby, of means for lubricating the latter comprising a tubular condenser operatively connected at one end to the exhaust pipe and at its other end discharging into the air compressing cylinder, the condenser pipe at its inlet end having a restricted inlet opening and at its outlet end having a restricted outlet opening.

3. The combination with a steam cylinder having an exhaust pipe and an air compressing cylinder operated thereby, of means for lubricating the latter comprising a tubular condenser operatively connected at one end to the exhaust pipe and at its other end discharging into the air compressing cylinder, the condenser pipe at its inlet end having a restricted inlet opening and at its outlet end having a restricted outlet opening and at its outlet end having a nipple mounted within the pipe and extending away from the outlet thereof, said nipple having a longitudinally extending bore, the bore at its outlet end being contracted to provide a relatively small outlet orifice.

4. The combination with a low pressure steam cylinder and a high pressure steam cylinder, a high pressure air compressing cylinder and a low pressure air compressing cylinder, the air compressing cylinders being operated by the steam cylinders, pistons

connecting the low pressure steam cylinder with the high pressure air cylinder and the high pressure steam cylinder with the low pressure air cylinder, the low pressure air cylinder having an exhaust pipe, of a condenser pipe operatively connected to the exhaust pipe and discharging into the low pressure air cylinder, said condenser pipe having a restricted inlet opening at its inlet 10 end and a restricted discharge opening at its outlet end.

5. The combination with an engine and an air compressing cylinder operated thereby, the engine including a steam cylinder 15 having an exhaust, of means for lubricating the air compressing cylinder including a condenser leading from the exhaust pipe of the steam cylinder and discharging into the air compressing cylinder, and means at the outlet end of said condenser for retarding the flow of condensate to the air cylinder.

6. The combination with a high pressure steam cylinder and a low pressure steam cylinder, a low pressure air cylinder and a high pressure air cylinder coacting with the high and low pressure steam cylinders, of means for lubricating the air compressing cylinders including a condenser, the condenser being operatively connected at one 25 end to the exhaust pipe of the low pressure steam cylinder, the condenser having branches discharging into the high and low pressure air cylinders respectively, and means at the outlet ends of the condenser 30 for retarding the flow of condensate into the high and low pressure air cylinders, said means including a trap.

7. The combination with a steam cylinder having an exhaust pipe and an air compressing cylinder operated thereby, means for lubricating the latter comprising a steam condensing member, means connecting the condensing member to the exhaust pipe including a member having a restricted orifice and a screen, and means for connecting the condensing member with the air cylinder including a member having a restricted orifice and acting as a trap.

8. The combination with a steam cylinder having an exhaust pipe, an air compressing cylinder coacting with the steam cylinder and operated thereby, means for carrying lubricant into the interior of the steam cylinder, of means for lubricating the air cylinder comprising a steam condensing member connected at one end to the exhaust pipe of the steam cylinder and having a discharge outlet connected to the air cylinder, and means at the inlet and outlet ends of the condenser for retarding the flow of fluid 50 therefrom.

9. The combination with a steam cylinder having an exhaust pipe, an air compressing cylinder coacting with the steam cylinder and operated thereby, and means for carrying lubricant into the interior of the steam cylinder, of means for lubricating the air cylinder comprising a steam condensing member connected to one end of the exhaust pipe of the steam cylinder and having a discharge outlet connected to the air cylinder.

In testimony whereof I hereunto affix my signature.

WILLIAM E. FARLEY.
